[57] CLAIM

The ornamental design for a golf putter head, as shown and described.

DESCRIPTION

FIG. 1 is a front prospective view, seen from above, of a golf putter according to my new design;

FIG. 2 is a right side perspective view, seen from above;

FIG. 3 is a rear perspective view thereof, seen from the right side and from above;

FIG. 4 is a left side prospective view thereof, seen from below;

FIG. 5 is a top plan view thereof;

FIG. 6 is a front elevational view thereof;

FIG. 7 is a left side elevational view thereof; and,

FIG. 8 is a right side elevational view thereof.

FIG. 1 additionally shows, in broken lines, the lower portion of a golf club shaft which will be secured to the putter head in a complete putter. The shaft does not form part of the novel design.
